UNITED STATES PATENT OFFICE.

CHARLES WILDER, OF EAST SAN DIEGO, CALIFORNIA, ASSIGNOR OF ONE-HALF TO
GEORGE W. THOMPSON, OF SAN DIEGO, CALIFORNIA.

MEASURING DEVICE.

1,222,168.

Specification of Letters Patent.

Patented Apr. 10, 1917.

Application filed January 25, 1915. Serial No. 4,164.

To all whom it may concern:

Be it known that I, CHARLES WILDER, a subject of the King of England, and a resident of East San Diego, in the county of San Diego and State of California, have invented certain new and useful Improvements in Measuring Devices, of which the following is a specification.

My invention relates to a device for taking measurements more particularly to be used by carpenters and mechanics for taking measurements for fitting purposes.

The objects of my invention are, first, to provide a device of this class which is very simple and economical of construction, second, to provide a device of this class the clamping portion of which is readily applicable to different sized strips of wood for measuring purposes which may be picked up on the job for use, third, to provide a device of this class which will readily hold the two strips in their proper position and not allow them to slip and fourth, to provide a clamping device of this class that may be used for other purposes by a carpenter or mechanic.

With these and other objects in view as will appear hereinafter my invention consists of certain novel features of construction, combination and arrangement of parts as will be hereinafter described in detail and particularly set forth in the appended claim, reference being had to the accompanying drawings and to the characters of reference thereon which form a part of this specification, in which:

Figure 1 is a perspective view of my device complete showing fragmentary portions only of the wood strips, Fig. 2 is a sectional view of the clamping portion of my device shown closed up more than that of Fig. 1.

Similar characters of reference refer to similar parts throughout the several views.

The strip 1, strip 2, clamp piece 3, clamp piece 4, and cam piece 5 constitute the principal parts of my device.

The strip 1 may be any ordinary strip of the usual seven-eighths inch thickness that may be picked up on the job and for some purposes where it is desired to use a measuring piece of the same length for several times it is desirable to fasten this strip 1 at a suitable place to the clamp which is done by means of the screw 3^a in the

clamp piece 3 or a couple of small nails may be driven through the holes 3^b into the strip 1 which will secure this strip 1 to the clamp piece 4 but it extends in the opposite direction from the strip 1 so that the extended ends of the strips 1 and 2 may be placed in the position desired for the measuring and then clamped together. The clamp consists of the two L shaped metallic pieces 3 and 4 and the cam piece 5. The L shaped metallic piece 3 is provided with two lugs 3^c preferably integral with the sides of the metal and adapted to extend over the sides of the clamp piece 4 and the clamp piece 4 is provided with two lugs 4^a, also integral with the sides of the metal extending over the sides of the clamp piece 3. These clamp pieces 3 and 4 on the extended ends 3^d and 4^b are knurled on their inner surfaces as shown best in Fig. 2 of the drawing. These two clamp pieces 3 and 4 are held in sliding position to each other by means of the rivet 5^a, which is secured in the piece 3 but is mounted in a slot 4^e in the clamp piece 4 and extends through the cam piece 5 providing a pivotal mounting for said cam piece 5 and leaving a space between the cam piece 5 and the clamp piece 3 sufficient to allow the clamp piece 4 to reciprocate between these two pieces. The cam piece 5 is shaped as shown in the drawings and is provided with a semi-circular slot 5^b therein. This semi-circular slot 5^b is eccentric with the rivet 5^a upon which the cam piece 5 is pivotally mounted, and rigidly secured to the clamp piece 4 is a lug 4^d adapted to extend through the semi-circular slot 5^b, so that when the cam piece 5 is turned on the rivet 5^a the clamp piece 4 will be moved on said rivet relatively to the piece 3, thus providing a clamp for clamping the strips 1 and 2 together. The cam piece 5 is provided with two integrally extended lugs 5^c to facilitate the movement of the cam piece by the hand of the operator.

Though I have shown and described a particular construction, combination and arrangement of parts I do not wish to be limited to this particular construction, combination and arrangement, but desire to include in the purview of my invention the construction, combination and arrangement substantially as set forth in the appended claim.

It is obvious that with this construction

there is provided a device for measuring purposes which is very simple of construction and easy of operation; that the strips 1 and 2 may be readily picked up on the 5 job by a carpenter or mechanic and readily secured to the clamp piece if desired; that the clamp piece will secure the two strips together so that measurements may be taken accurately with the device as a whole; that 10 the strips 1 and 2 do not need to be carried with the clamp but may be thrown away when through with them on the particular job and may be substituted with others at any time; that the clamp may be used for 15 clamping small pieces together for gluing purposes and for other purposes by the carpenter or mechanic as desired.

Having thus described my invention what I claim as new and desire to secure by Letters Patent is:

Copies of this patent may be obtained for five cents each, by addressing the "Commissioner of Patents, Washington, D. C."

In a device of the class described, the combination of an L shaped piece provided with a slot therein and a circular lug projecting therefrom, another L shaped metallic piece slideable relatively thereto by means 25 of a rivet engaging said slot and means for sliding and holding these two pieces relatively to each other comprising a metallic piece provided with a semi-circular slot 30 therein adapted to fit over said circular lug and to slide thereon, pivotally and irre- movably mounted on said rivet eccentrically to said slot.

In testimony whereof, I have hereunto subscribed my name in the presence of two 35 subscribing witnesses.

CHARLES WILDER.
